[57] CLAIM

The ornamental design for absorber of electric noise, as shown and described.

DESCRIPTION

FIG. 1 is a front elevational view of an Absorber of Electrical Noise showing my new design.

FIG. 2 is a rear elevational view thereof.

FIG. 3 is a top plan view thereof.

FIG. 4 is a bottom plan view thereof.

FIG. 5 is a left end elevational view thereof.

FIG. 6 is a right end elevational view thereof.

FIG. 7 is a perspective view as seen from the front and upper right.

FIG. 8 is a front elevational view of an absorber of electrical noise showing a second embodiment of my new design;

FIG. 9 is a rear elevational view thereof;

FIG. 10 is a top plan view thereof;

FIG. 11 is a bottom plan view thereof;

FIG. 12 is a right end elevational view thereof;

FIG. 13 is a left end elevational view thereof;

FIG. 14 is a front and upper right perspective view thereof;

FIG. 15 is a back and lower right perspective view thereof.
